CLAIM

The ornamental design for an electrocardiograph recorder, as shown and described.

DESCRIPTION

FIG. 1 is a front perspective view of an electrocardiograph (ECG) recorder in accordance with our new and ornamental design;

FIG. 2 is a front view of the ECG recorder illustrated in FIG. 1;

FIG. 3 is a rear view of the ECG recorder illustrated in FIG. 1;

FIG. 4 is a left side view of the ECG recorder illustrated in FIG. 1;

FIG. 5 is a right side view of the ECG recorder illustrated in FIG. 1;

FIG. 6 is a top plan view of the ECG recorder illustrated in FIG. 1;

FIG. 7 is a bottom plan view of the ECG recorder illustrated in FIG. 1;

FIG. 8 is a front perspective view of the ECG recorder shown attached to a base; and,

FIG. 9 is a front perspective view of the ECG recorder shown attached to a power supply charger.

The broken lines in FIG. 7 showing portions of the ECG recorder that form no part of the claimed design. Additionally, the broken lines showing of the base in FIG. 8 and the broken lines showing of the power supply charger in FIG. 9 illustrate environment and form no part of the claimed design.

1 Claim, 9 Drawing Sheets
